ROLLER CONVEYER

Hubert M. Rishel, Edwardsville, Ill., assignor to
 Mathews Conveyer Company, Ellwood City, Pa.,
 a corporation of Pennsylvania

Application March 23, 1936, Serial No. 70,204

7 Claims. (Cl. 193—35)

This invention relates to new and useful improvements in conveyers and more particularly to spring mounted conveyers of the general character disclosed in my co-pending applications 5 Serial Nos. 70,202 and 70,203, each filed March 23, 1936.

An object of the present invention is to provide a simple and inexpensive conveyer unit comprising a supporting member having means for resiliently supporting a conveyer roller therein, and whereby the spring means is retained under a fixed compression.

A further object is to provide a conveyer unit comprising a supporting member having oppositely disposed guides therein adapted to receive suitable springs, and bearing elements mounted on said springs and supporting a conveyer roller, said bearing elements being adapted to engage means on the supporting member for limiting downward movement of the conveyer roller against the pre-compression of the springs, and said base member having means for limiting upward movement of the roller and for retaining the springs under a predetermined compression.

20 A further object is to provide a conveyer comprising a plurality of independent conveyer units adapted to be aligned to provide a longitudinally extending conveyer, and each conveyer roller being supported upon suitable spring elements 30 which are retained under a predetermined compression, determined by the weight of the load to be conveyed, and the supporting member of each unit having upright portions extending above the upper portions of the rollers and serving as guards to retain elongated articles, such as rails, on the conveyer.

25 A further object is to provide a conveyer unit comprising a supporting member having a conveyer roller resiliently mounted therein, and 40 said unit being self-contained whereby it readily lends itself for use in various types of roller conveyer installations.

Other objects of the invention will appear from the following description and accompanying 45 drawing and will be pointed out in the annexed claims.

In the accompanying drawing there has been disclosed a structure designed to carry out the various objects of the invention, but it is to be understood that the invention is not confined to the exact features shown as various changes may be made within the scope of the claims which follow.

In the drawing:

55 Figure 1 is an elevational view, partially in sec-

tion, showing the general construction of my improved conveyer unit;

Figure 2 is a sectional plan view on the line 2—2 of Figure 1;

Figure 3 is an end view of Figure 1;

Figure 4 is a view, showing one of the bearing elements removed from the supporting member of the unit;

Figure 5 is a view on a relatively smaller scale, illustrating a conveyer constructed in accordance with the present invention;

Figure 6 is a plan view showing a conveyer having continuous guard rails; and

Figure 7 is a cross-sectional view of Figure 6.

The novel conveyer unit herein disclosed is 15 shown comprising a supporting member, generally indicated by the numeral 2, and comprising a base portion 3 having upright portions 4 co-operating to provide vertical guides for a pair of resilient elements or springs 5, shown supported in said guides with their lower ends seated 20 on the base portion 3 of the member 2.

Suitable bearing elements 6, each having a depending portion 7, are supported on the springs 5, with their depending portions 7 fitting in the springs 5, as best shown in Figure 1. An axle 8 is supported in the bearing elements 6, and carries a suitable conveyer roller 9, preferably rotatably mounted upon the axle 8 in the usual manner. The outer ends of the bearing elements 6 are preferably shaped as shown at 11 in Figure 1, thereby to provide abutment shoulders for suitable retaining pins 12, secured to the terminals of the axle 8, as clearly illustrated in Figures 1 and 3. In the structure, as here shown, the pins 12 prevent relative rotation of the axle and also axial movement thereof. If desired, other suitable means may be provided for accomplishing the same result.

Means is provided for retaining the springs 5 under a predetermined compression, and, in the present instance, is shown comprising horizontal wall portions 13, integrally formed with upright portions 14 of the supporting member, as clearly shown in Figures 1 and 3.

The guides or recesses 4 are open at their inner sides, whereby the spring elements 5 may readily be inserted therein, after the bearing elements 6 are mounted thereon, as clearly illustrated at the right hand side of Figure 2. Before the springs 5, with the bearing elements 6 supported thereon, are inserted into the recesses 4, the springs are compressed sufficiently to allow the upper portions of the bearing elements to pass beneath the abutment walls 13, as will readily be understood 55

by reference to Figure 1. The axle 8 may be inserted through the apertures in the bearing elements 6 and the bearings of the roller 9, after the springs and bearing elements have been properly positioned in the guides 4, as shown in Figure 1.

The pre-compression of the springs is an important factor in the construction of the conveyer unit, and may be determined by the weight 10 of the load to be transported over the conveyer. In other words, as a specific example, if the safe carrying load of the roller 9 is 300 pounds, the springs are preferably pre-compressed to at least 15 300 pounds or 150 pounds per spring, before being inserted into the recesses 4, whereby the springs do not substantially yield or flex, when a normal load is supported on the roller. However, when an overload, or a load weighing in 20 excess of the safe carrying capacity of the roller, or, in the present instance, over 300 pounds, is imposed on the roller, the springs 5 will flex and permit the roller to yield to the weight of the overload, whereby damage to the roller and its 25 bearings is substantially eliminated. In certain instances where the loads to be transported are of such character that they will be supported on skids which engage a plurality of rollers, it will be obvious that the skids may be of such 30 length as to engage any desired number of rollers, and hence the weight will be proportionally distributed over those rollers engaged by the skids. In such instance, each roller engaged by the skids as the load passes thereover may carry considerably less than 300 pounds and hence, if desired, 35 the springs of each roller may be pre-compressed a correspondingly less amount. In the simple structure herein disclosed, no means is provided for relatively varying the pre-compression of the springs 5.

If desired, the supporting member 2 may be provided with suitable anchor lugs, such as shown at 15 in Figure 3, adapted to be embedded in a concrete foundation 16, indicated by the broken line in Figure 3. Suitable anchor bolts may be 40 used in lieu of the lugs 15, if desired.

In Figure 5, there is shown a conveyer comprising a plurality of conveyer units arranged in longitudinal alignment, whereby articles such as 50 rails or other elongated members, may readily be transported over the conveyer with a minimum of effort. Because of the conveyer rollers 8 being supported upon the springs 5, the rollers are 55 free to yield in a vertical plane when subjected to an overload, which may be caused from variations in the bottom of the load being transported over the conveyer. Also, by thus permitting the rollers to yield when subjected to an overload, damage to the roller and its bearings is substantially eliminated, and each roller will contact 60 with the load and carry approximately its proportionate share of the weight thereof. The conveyer unit is very simple and inexpensive, as will readily be understood by reference to Figures 1, 2, and 3, and may be manufactured in quantity production at a comparatively small cost. The upper portions 17 of the side members 14 of the supporting member 2, project above the uppermost portions of the rollers 8, and may serve as 65 guards for retaining the articles on the conveyer, while in transit, as will readily be understood by reference to Figure 1.

Figures 6 and 7 illustrate a conveyer comprising a plurality of conveyer units somewhat similar in construction to the one shown in the previous 70

figure, but wherein the upright portions 14 of the supporting member 2 have longitudinally extending guard rails 18 suitably secured thereto to retain articles on the conveyer.

The term "substantial pre-compression" as used in the claims, denotes a pre-compression greater than the compression caused by the normal weight of each roller and its associated parts.

I claim as my invention:

1. A conveyer composed of a plurality of independent conveyer units arranged to provide a suitable conveyer bed, each unit comprising a supporting member having a plurality of resilient elements mounted thereon, a conveyer roller mounted on the resilient elements of each unit, 10 means for retaining said elements under a substantial pre-compression independent of the weight of the roller and its associated parts, and means on each supporting member projecting above the uppermost portions of the conveyer rollers 15 and cooperating to provide guard rails to retain articles on the conveyer.

2. A conveyer composed of a plurality of independent conveyer units, each unit comprising a supporting member having means for anchoring 25 it to a suitable foundation, springs mounted on each supporting member and carrying a conveyer roller, said supporting members having upright side portions providing guides for said springs, means for retaining the springs under a substantial pre-compression independent of the weight 30 of the roller and its associated parts, and said upright side portions extending above the uppermost portions of the conveyer rollers of said units and cooperating to retain articles on the 35 conveyer.

3. A conveyer unit comprising a base member having upwardly extending vertical guides thereon, springs within said guides, an axle supported on the springs, a conveyer roller mounted on the 40 axle, and means for retaining the springs under a substantial pre-compression independent of the weight of the roller and its associated parts.

4. A conveyer unit comprising a base member having upright guides thereon, springs in said 45 guides, an axle supported on an element engaged with said springs, said element being positioned for vertical movement in said guides, a conveyer roller mounted on the axle, and means associated with the guides for retaining the springs under a substantial pre-compression independent of the 50 weight of the conveyer roller and its associated parts.

5. A conveyer unit comprising a supporting member having oppositely disposed guides thereon, open at their upper ends, springs in said 55 guides, supporting elements having depending portions fitting in said springs, a conveyer roller supported on said elements, and means for retaining the springs under a substantial pre-compression independent of the weight of the conveyer roller and its associated parts.

6. A conveyer unit comprising a supporting member having oppositely disposed guides thereon, springs in said guides, supporting elements having depending portions fitting in said springs, and whose lower ends are spaced from the bottom wall of the supporting member, thereby to 65 permit limited downward movement of the elements, a conveyer roller supported in said elements, and non-adjustable means for retaining said springs under a substantial pre-compression independent of the weight of the conveyer roller and its associated parts.

7. A conveyer unit comprising a supporting 70

member having oppositely disposed guides thereon, springs in said guides, supporting elements having depending portions fitting in said springs, and whose lower ends are spaced from the bottom 5 wall of the supporting member, thereby to permit limited downward movement of said elements, an axle supported by said elements and carrying

a conveyer roller, and means fixed to the supporting member for limiting upward movement of the conveyer roller, said fixed means serving to maintain said springs and roller mounting under a substantial pre-compression independent of 5 the weight of the roller and its associated parts.
